UNITED STATES PATENT OFFICE.

JAMES E. McDADE, OF CHICAGO, ILLINOIS.

GRAPH CHART.

Application filed February 27, 1922. Serial No. 539,345.

To all whom it may concern:

Be it known that I, JAMES E. McDADE, a citizen of the United States, residing at Chicago, in the county of Cook and State 5 of Illinois, have invented certain new and useful Improvements in Graph Charts, of which the following is a specification.

My invention relates to charts, and particularly to charts so constructed that graphs 10 for various purposes may readily be indicated thereon.

One of the objects of my invention is the provision of a chart for this purpose of simplified and inexpensive construction, the 15 foundation structure of which consists of alternately arranged, substantially parallelly extending rigid and flexible portions, an indicating member being movably associated with each of the rigid portions, whereby the 20 chart may be readily rolled or folded into compact form and stored away when not in use or easily transported from place to place as is often desirable when the chart is used by a person giving lectures in different 25 communities. In its preferred form the foundation structure of the chart consists of a sheet of flexible material, for example, paper, to one side of which are secured spaced, substantially parallelly extending 30 relatively rigid members, which members may be formed of any suitable material, for example, heavy press-board or wood, the sheet of flexible material readily bending between the rigid members so that the chart 35 may be easily rolled or folded into compact form.

A further object of my invention is the provision of a chart so constructed that any desired designation or indicia may be displayed thereon in substantial alignment with the respective indicating members of the chart, the foundation structure of the chart preferably being formed so as to provide a plurality of pockets adapted to receive display cards bearing the desired designations or indicia which display cards, when properly inserted in the pockets, are in substantial alignment with the respective indicating members.

50 In its preferred form the invention also contemplates the provision of a pair of pockets extending substantially parallelly with the indicating members in one of which a card bearing a suitable scale may be inserted and in the other cards bearing any de-

sired designations or indicia, for example, the subject matter under consideration, may be inserted.

A further object of my invention is the provision of a plurality of indicating members in association with each rigid member of the foundation structure, these indicating members preferably being in the form of endless tapes extending longitudinally around said rigid members, and having a distinctive indicating portion, whereby comparative graphs may be readily made, for example, showing the amount of any given product produced in certain States during one year as compared with the amount produced in the same States during another year.

The invention consists in the novel constructions and arrangements to be herein-after described and claimed for carrying out 75 the above stated objects and such other objects as will appear from the following description of a certain preferred embodiment illustrated in the accompanying drawings, wherein—

Fig. 1 is a front elevational view of a chart embodying the principles of my invention;

Figs. 2, 3 and 4 are sectional views, on an enlarged scale, taken on the lines 2—2, 3—3 85 and 4—4, respectively, of Fig. 1; and

Fig. 5 is a rear elevational view of one of the rigid members which support the indicating member or members, as the case may be.

Like characters of reference designate like parts in the several views.

Referring now to the accompanying drawings, the foundation structure of the chart comprises a sheet 10 which may be of any suitable material, for example, medium weight manila paper, to the back of which a plurality of spaced, substantially parallelly extending strips 11 are secured. The strips 11 may be made of any suitable material, for example, press-board or wood, they being relatively rigid with respect to the sheet 10. The strips may be secured to the back of the sheet 10 in any desired manner, for example, by applying glue to the 95 face sides of the respective strips and pressing them against the back of the sheet; and, if it is desired to reinforce the structure further, a strip 12 of cloth or paper may be glued to each of the strips 11, the strips 12 100

90

100

105

110

being somewhat wider than the strips 11 and being glued to the back of the sheet 10.

In the form of my invention illustrated, a pair of indicating members is provided for each of the rigid strips 11, the indicating members being in the form of endless tapes 13 and 14, extending longitudinally around the strips 11. The ends of the reinforcing strips 11 may be formed so as to provide recesses 15 in each end, which recesses register with slots 16 provided in sheet 10, see Figs. 4 and 5, the endless tapes 13 and 14, respectively, extending through the slots 16 provided in the sheet 10, the recesses 15 and around the strips 11 as shown in Fig. 4. The recesses 15 are deep enough and the endless tapes are stretched taut enough to insure the tapes being at all times in operative position on the strips 11. The recesses 15 are not essential as the slots 16 in the sheet 10 will suffice to maintain the tapes in operative position on the strips 11.

That portion of the sheet 10 over which the tapes extend is preferably provided with columnar rulings 17 extending substantially at right angles to the tapes. A scale 18 is arranged on the foundation structure of the chart in association with the columnar rulings 17, the preferred arrangement being to form the sheet 10 so as to provide a pocket 19 extending substantially parallel with the endless tapes in which a display card 20 may be inserted, the display card bearing the desired scale 18.

The foundation structure may also be formed with a pocket 21 extending substantially parallel with the pocket 19 in which display cards 22 may be inserted, these cards bearing any desired indicia or designation, for example, the subject matter and the period of time under consideration.

The foundation structure is also preferably arranged so that designations or indicia may be displayed substantially in alignment with the respective pairs of tapes, the preferred arrangement being to construct the foundation structure with a plurality of pockets 23 in which display cards 24 bearing the desired designations or indicia may be inserted, the pockets 23 being so positioned that when the display cards are properly inserted therein, the respective display cards are in substantial alignment with the respective pairs of tapes.

Each tape comprises two portions which are distinctively colored relative to each other, for example, the portions 13^a of the tape 13 may be white while the portion 13^b of said tape may be green, the meeting ends of the two distinctive colored portions on the face side of the chart being fastened together and left to project sufficiently beyond the face of the chart to provide a grip portion 13^c whereby the tape may be readily

shifted longitudinally relative to the rigid strips 11. The portion 14^a of the tape 14 may be white and the portion 14^b thereof may be blue, the meeting edges thereof on the face side of the chart being united so as to provide a grip portion 14^c.

The chart is preferably constructed so that it may be suspended from a hook on the wall and to that end horizontally extending strips 25 may be attached to the top and bottom edges of the foundation structure, and the upper strip may be provided with screw eyes 26 for fastening a suspension cord 27. The vertical edges of the foundation structure may be taped with cloth strips 28 to reinforce the same if desired.

The extra material required in the construction of the pockets 23 substantially compensates for the bulkiness of the strips 11, which, it will be noted, do not extend behind the pockets 23. The portions of the sheet 10 extending between the strips 11 readily flexes and permits the chart to be easily rolled or folded into compact form when it is not in use and when in this form the chart occupies but a small amount of space and may be easily stored away or conveniently transported from place to place.

The manner in which my chart may be used will be clearly understood by reference to Fig. 1 of the drawings, the chart being arranged, for the purpose of illustration, to show graphically the amount of coal produced in certain States for the year 1920 as compared with the year 1910, the scale inserted in the pocket 19 being so arranged that each vertical columnar ruling on the sheet 10 represents a million tons and cards bearing the names of the principal coal producing States being inserted in the respective pockets 23. By reference to a suitable table of statistics the operator may readily adjust the upper tape of each pair to bring the respective grip portions 13^c at the proper position with reference to the scale 18 so that the quantity of coal produced in each State for the year 1910 may be readily ascertained by noting the respective positions of the grip portions 13^c or the length of the respective green portions of the upper tapes. In a like manner the operator may readily adjust the lower tape of each pair to bring the respective grip portions 14^c into proper position with reference to the scale whereby the amount of coal produced in the same States for the year 1920 may be readily ascertained by noting the respective positions of the grip portions 14^c or the length of the respective blue portions of the lower tapes.

The uses to which a chart of this type may be put are almost innumerable, for example, it may be used to display the returns of an election, particularly the returns of one election as compared with those of another; or, it may be used by a salesmanager

to keep tab of the amount of sales made by one salesman with respect to the sales made by other salesmen for any given period of time, or for a given period of time as compared with the sales during another period of time; or, it may be used to show the production of a given commodity in various districts or States for a given period of time as compared with another period of time as illustrated in Fig. 1, or the relative values of commodities produced in a given district for a given period of time as compared with another period of time, etc.

I do not intend to limit my invention to the details of construction shown and described except only in so far as certain of the appended claims are specifically so limited, as it will be obvious that modifications may be made without departing from the principles of the invention.

I claim:

1. A chart of the class described comprising a foundation structure consisting of alternately disposed substantially parallelly extending rigid and flexible portions, so constructed and arranged that the chart may be brought into compact form, and an indicating member movably associated with each of said rigid portions, for the purpose specified.

2. A chart of the class described comprising a foundation structure consisting of alternately arranged substantially parallelly extending rigid and flexible portions, and an endless tape extending longitudinally around each of said rigid portions, said tapes having distinctive portions and being movable relatively to said rigid portions, respectively, for the purpose specified.

3. A chart of the class described comprising a foundation structure adapted to be brought into compact form and consisting of a sheet of flexible material to one side of which are secured spaced, substantially parallelly extending relatively rigid members, and an indicating member movably associated with each of said rigid members, for the purpose specified.

4. A chart of the class described comprising a foundation structure adapted to

be brought into compact form and consisting of a sheet of flexible material to one side of which are secured spaced, substantially parallelly extending relatively rigid members, and an endless tape extending longitudinally around each of said rigid members, said tapes having distinctive portions and being movable relatively to said rigid members, respectively, for the purpose specified.

5. A chart of the class described comprising a foundation structure adapted to be brought into compact form and consisting of a sheet of flexible material to one side of which are secured spaced, substantially parallelly extending relatively rigid members, and an indicating member movably associated with each of said rigid members, said structure having a pair of pockets arranged substantially parallel with said rigid members, one of said pockets being adapted to receive cards bearing display matter and the others adapted to receive a card bearing a scale, said structure also having pockets arranged in substantial alignment with said respective indicating members and adapted to receive cards bearing display matter, for the purpose specified.

6. A chart of the class described comprising a foundation structure consisting of a sheet of flexible material to one side of which are secured spaced, substantially parallelly extending relatively rigid members, and a plurality of endless tapes extending longitudinally around each of said rigid members, said tapes having distinctive portions and being movable relatively to said rigid members, respectively, said structure having a pair of pockets arranged substantially parallel with said rigid members, one of said pockets being adapted to receive cards bearing display matter and the other adapted to receive a card bearing a scale, said structure also having pockets arranged in substantial alignment with said respective indicating members and adapted to receive cards bearing display matter, for the purpose specified.

JAMES E. McDADE.
